(57) **CLAIM**

We claim the ornamental design for a personnel lift vehicle, as shown and described.

DESCRIPTION

FIG. 1 is a front perspective view of a personnel lift vehicle according to our new design;

FIG. 2 is a rear perspective view of the embodiment in FIG. 1; FIG. 3 is a rear elevational view of the embodiment in FIG. 1; FIG. 4 is a right side elevational view of the embodiment in FIG. 1;

FIG. 5 is a left side elevational view of the embodiment in FIG. 1;

FIG. 6 is a front elevational view of the embodiment in FIG. 1;

FIG. 7 is a top plan view of the embodiment in FIG. 1; and, FIG. 8 is a bottom plan view of the embodiment in FIG. 1. The broken lines shown in the figures are included for the purpose of illustrating portions of the personnel lift vehicle and form no part of the claimed design.
